UNITED STATES PATENT OFFICE.

JACOB H. BECKMANN, OF NEW YORK, N. Y.

DESIGN FOR A WATCHCASE.

Application filed September 24, 1927. Serial No. 23,545. Term of patent 7 years.

To all whom it may concern:

Be it known that I, JACOB H. BECKMANN, a citizen of Hungary, residing at New York, in the county of New York and State of New York, have invented a new, original, and ornamental Design for Watchcases, of which the following is a specification, reference being had to the accompanying drawing, forming a part thereof.

In the drawing:

Fig. 1 is a front view of a watchcase showing my new design, and

Fig. 2 is a rear view thereof, and

Fig. 3 is a top edge view of the watchcase.

I claim:

The ornamental design for a watchcase, as shown.

JACOB H. BECKMANN.
